Patented Dec. 13, 1921.

H. C. BLANK,

By
Geo. P. Kimmel, Attorney

UNITED STATES PATENT OFFICE.

HERMAN C. BLANK, OF CHICAGO, ILLINOIS.

BUILDING-TILE.

1,400,407.

Specification of Letters Patent.

Patented Dec. 13, 1921.

Application filed November 22, 1920. Serial No. 425,684.

To all whom it may concern:

Be it known that I, HERMAN C. BLANK, a citizen of the United States, residing at Chicago, in the county of Cook and State of Illinois, have invented certain new and useful Improvements in a Building-Tile, of which the following is a specification.

This invention relates to building blocks or tiles, and has for one of its objects to improve the construction and increase the heat and cold resisting qualities without material increase of expense or weight.

Another object of the invention is to produce a wall unit or tile having means whereby the joints between the units are rendered air proof and insulated against the passage of heat or cold.

With these and other objects in view, the invention consists in certain novel features of construction as hereinafter shown and described and then specifically pointed out in the claim, and in the drawings illustrative of the preferred embodiment of the invention.

Figure 1 is a perspective view of one of the improved wall units or tiles.

Fig. 2 is a side elevation, partly in section, of a portion of a wall constructed of the improved wall units or tiles.

Fig. 3 is a plan view of a plurality of the improved wall units or tiles engaging end to end and without the bonding cement.

Fig. 4 is a perspective view of a modified form of the tile.

The improved wall units or tiles each consists of a hollow open ended structure, preferably oblong in outline and each including side walls 10 and 11, top 12, bottom 13 and a longitudinally directed dividing web 14, the web being preferably thicker than the walls, as shown.

Formed in the end of each web 14 is a groove or channel 15, and likewise formed in the top and bottom walls are like grooves or channels 16 and 17, the grooves or channels merging one into the other at their ends, thus forming a continuous groove or channel around each unit.

The vertical end channels 15 form spaces

to receive bonding cement or mortar indicated at 18 while the longitudinal channels 16 and 17 form dead air spaces between the units.

By this simple means the units are united by air, moisture, heat or cold proof joints and the cells at the opposite sides of the partitions or webs maintained entirely and continuously separated, and circulation between the cells transversely of the wall prevented.

The channels or groove 15 are preferably rounded at their ends and the grooves also preferably convex transversely to insure the more ready entrance of the mortar or other cement, thus insuring an air and moisture proof mortar keyed joint.

When properly constructed the improved tile will not need furring or lathing on the inside to receive plaster, and can also be constructed with exterior channels or grooves 19 to secure the requisite bonding of the plaster or stucco material.

In Fig. 4 the improvement is shown applied to a single cell tile, or one without the dividing partition.

The improved tile is adaptable to all climates, or conditions of weather, and will effectually resist the passage of heat, cold or moisture and is likewise sound proof and fire proof.

The preferred embodiment of the invention is disclosed in the drawings and set forth in the specification, but it will be understood that any modifications within the scope of the claimed invention may be made in the construction without departing from the principle of the invention or sacrificing any of its advantages.

I claim:

A tile unit having an opening extending entirely therethrough and with walls of substantially uniform thickness, a central web dividing the opening, and a continuous groove in the upper and lower walls of the unit and in the ends of the web.

In testimony whereof, I affix my signature hereto.

HERMAN C. BLANK.
